attty.

UNITED STATES PATENT OFFICE.

FREDERICK O. KILGORE, OF SOMERVILLE, MASSACHUSETTS, ASSIGNOR TO SPRAY PRIMER COMPANY, OF BOSTON, MASSACHUSETTS, A CORPORATION OF MASSACHUSETTS.

PRIMER.

1,265,919.

Specification of Letters Patent. Patented May 14, 1918.

Application filed February 16, 1916. Serial No. 78,747.

To all whom it may concern:

Be it known that I, FREDERICK O. KILGORE, a citizen of the United States, and a resident of Somerville, in the county of Middlesex and State of Massachusetts, have invented an Improvement in Primers, of which the following description, in connection with the accompanying drawings, is a specification, like characters on the drawings representing like parts.

This invention relates to an apparatus for priming internal combustion motors, and has for its object to provide a simple, efficient and inexpensive apparatus, which is especially applicable to automobiles, motor cycles, motor boats and the like.

The apparatus consists essentially of a pump provided with a cylinder having a fluid inlet port and a fluid outlet port, said ports being controlled by valves which automatically respond to the movement of the piston in said cylinder. Provision is also made for positively moving one and preferably both of said valves, so as to insure that the said valves are unaffected by the suction of the motor, as will be described. Provision is made for automatically moving said piston on its suction stroke so as to maintain a charge of gasolene or other motive fluid in the pump cylinder when the apparatus is not being used, as will be described.

These and other features of this invention will be pointed out in the claims at the end of this specification.

Figure 1 represents a portion of an automobile provided with a priming apparatus embodying this invention.

Fig. 2, a longitudinal section of the apparatus with the parts in the position they occupy when the piston is at the end of its suction stroke.

Fig. 3, a like section with the parts in the position they occupy when the piston is at the end of its forcing stroke.

Fig. 4, a detail in section with the valves in the position they occupy at the beginning of the suction stroke of the piston; and

50 Figs. 5 and 6, details to be referred to.

Referring to the drawings, *a* represents the cylinder of a pump, which is provided at one end with the head *b* and at its

opposite end with a head *c*, which has cast integral with it a hollow boss *d* extended 55 diametrically across the head *c*. The hollow boss *d* co-operates with the head *c* to form chambers 10, 12, which will be referred to as the inlet and outlet valve chambers.

The inlet valve chamber 10 contains within it an air inlet valve 13, which is herein shown as a disk of leather or other suitable material, which co-operates with the mouth of a fluid inlet port or passage 14, extended through a nipple 15, which has its inner end in threaded engagement with the walls of the chamber 10, and has its outer end externally threaded so as to be engaged by a nut 16, by means of which the fluid supply pipe 17 is detachably secured to the nipple 15. The outlet valve chamber 12 contains an outlet valve 20, herein shown as a disk of leather or other suitable material, which co-operates with the mouth of a fluid outlet port or passage 22, extended through a nipple 23, which is in threaded engagement with the walls of the chamber 12 and has its outer end externally threaded to be engaged by a nut 24, by means of which the fluid outlet pipe 25 is detachably secured to the nipple 23. Fluid tight joints between the pipes 17, 25, and the nipples 15, 23, may be obtained in a known manner by means of conical sleeves 27, 28, on the pipes 17, 25, being forced by the nuts 16, 24, against conical seats 29, 30, at the outer ends of the passages 14, 22, through the nipples. Provision is made for enabling the valves 13, 20, to be automatically opened 90 and also to be positively closed and held in their closed positions.

In the present instance, I have shown one construction for accomplishing these results.

To this end I employ two movable devices 95 31, 32, located in the valve chambers 10, 12, and preferably made as cylindrical blocks having on their inner ends concaved grooves 33, 34, with which co-operates a cone 35 fast on a rod 36, which forms an extension of 100 the piston rod 37 for the piston 38.

The movable block 32 carries the outlet valve 20, and in the present instance the said valve is fitted into a recess in the upper or outer end of the said block.

The block 32 is forced in one direction in

the valve chamber 12 by a spring 40 interposed between said block and the nipple 23, and said spring keeps the inner or under surface of the block 32 in engagement with either the rod 36 or the cone 35 as will be described.

The lower block 31 is provided on its inner or upper surface with the conical groove 33, which co-operates with the cone 35, and its lower or under surface has interposed between it and the inlet valve 13, a spring 41, which is shown as extended into a socket 42 in the under or outer surface of the block 31 and said spring acts to seat the inlet valve 13 and also to keep the block 31 in engagement with the rod 36 or the cone 35 as will be described.

The spring 41 is made sufficiently light to enable the inlet valve 13 to be lifted from its seat on the suction stroke of the piston 38 as represented in Fig. 4. The cone-carrying rod 36 is made of a suitable length to permit the piston 38 to travel a portion of its suction stroke in the direction indicated by the arrow 43, Figs. 2 and 3, before the cone is brought into engagement with the conical grooved surfaces of the blocks 31, 32, and on further movement of the piston on its suction stroke, the cone separates the blocks and moves them from substantially the position shown in Fig. 3, to that shown in Fig. 2, with the result that the inlet valve 13 is forced to its seat and is positively closed, and the outlet valve is forced to its seat, and is positively closed, as represented in Fig. 2.

The condition of the apparatus represented in Fig. 2 is what may be termed its normal condition with the cylinder *a* filled with gasoline or other motive fluid.

When it is desired to use the apparatus, the piston 38 is forced from the position shown in Fig. 2 to substantially that shown in Fig. 3, and as the piston is moved on its forward stroke, the cone 35 is withdrawn from between the blocks 31, 32, and the latter are permitted to be moved in the valve chambers by the springs 41, 40.

The spring 41 moves the block 31 toward the block 32 until the movement is arrested by the rod 36, and while this action is taking place, the inlet valve is kept closed by the pressure of the gasoline in front of the piston 38 assisted by the spring 41.

The spring 40 moves the block 32 toward the block 31 and removes the outlet valve 20 from its seat, thereby opening the outlet valve as shown in Fig. 3 and allowing a free passage for the gasoline from the cylinder *a* to the outlet pipe 25 through the port 50, valve chamber 12, and passage 22 in the nipple 23.

On the return stroke of the piston in the direction indicated by the arrow 43, the suction created by the piston lifts the inlet

valve 13 from its seat, as represented in Fig. 4, and draws gasoline or other motive fluid from the supply pipe 17 through the passage 14 into chamber 10 and thence through the port 51 into the cylinder. At or near the end of the suction stroke of the piston 38, the cone 35 is engaged with the conical grooves in the sliding blocks 31, 32, and moves the latter away from each other, so that when the piston has reached the end of its suction stroke and the cylinder *a* is filled with priming fluid, the sliding blocks will have been moved into position to positively close the inlet and outlet valves and especially the outlet valve 20, as the motor 53 with which the outlet pipe 25 is connected is rendered powerless to draw fluid from the pump cylinder *a*. The outlet valve 20 is attached to the movable block 32 and is engaged with its seat by movement of said block, whereas the inlet valve is seated by the block 31, and it will be noticed that the valves are locked or maintained in their closed position by the cone 35 as long as the piston 38 is at rest at the end of its suction stroke. As a result, the motor is powerless to draw gasoline from the cylinder or from the inlet pipe 17 through the cylinder while the priming apparatus is not being used.

When the piston 38 is moved on its pressure stroke, the cone 35 is moved into a chamber 54 formed by a cylinder 55, which is closed at its outer end and is in threaded engagement with a hollow boss 56 forming part of the walls of the valve chambers 10, 12.

The piston 38 is moved on its suction stroke by a spring 156, which is located in a hollow boss 57 extended from the front head *b* of the pump cylinder, and which is made of sufficient length to be extended through the dasher 58 of an automobile 59, to which dasher the priming apparatus is secured by a nut 60 and collar 61.

The piston rod 37 extends through the nut 60 and is provided with a removable handle 62. The nipple 23 to which the outlet pipe 25 is secured, preferably contains a check valve, herein shown as a ball 64, which is located in an enlarged portion of the passage 22 through the nipple and is adapted to close the narrower portion of said passage, which narrower portion is made in a removable member 65 of said nipple. The ball valve 64 is normally seated by a light spring 66.

The outlet pipe 25 is connected with the manifold of the motor 53, and the inlet pipe 17 is connected with the supply pipe 68 for the carburetor 69 at a point between the latter and the supply tank 70. The piston 38 may and preferably will be made as herein shown and consists of two cupped washers 71, 72, of leather or other suitable material, which are mounted on the piston 130

rod back to back and have their circumferences held in contact with the cylinder *a* by sheet metal disks 73, which are slotted at their circumferences to form spring fingers 74, and said disks and washers are clamped on the piston rod 36 between a metal disk 75 fast thereon, and a washer 76 and nut 77. The metal disk 75 is preferably soldered to the piston rod to prevent leakage of gasoline along the said rod.

5 In operation with the primer applied to the dasher of an automobile as shown in Fig. 1, the operator or driver of the car has only to push upon the head 62 of the piston rod when he desires to prime the motor, and after he removes his foot from the head 62, the spring 156 returns the piston to its normal position shown in Fig. 2, which movement of the piston not only fills the cylinder of the pump with gasoline but also positively closes the outlet valve and thereby prevents the suction of the motor from emptying the pump cylinder of its charge of gasoline.

25 I have herein shown one construction of apparatus for priming motors in which the outlet valve is automatically opened on the discharge stroke of the pump piston and positively closed on the suction stroke of said piston, but it is not desired to limit the invention to the particular construction herein shown.

Claims:

1. In an apparatus of the character described, in combination, a pump cylinder provided at its front and rear ends with heads, a hollow boss extended transversely across one of said heads and forming valve chambers, nipples detachably secured to said hollow boss and provided with passages forming a fluid inlet and a fluid outlet for said valve chambers, valves in said chambers, sliding blocks in said valve chambers movable toward and from each other and provided on their adjacent ends with conical grooves, a piston movable in said cylinder and provided with a piston rod having an extension extended between said sliding blocks, and a cone on said extension coöperating with the conical grooves of said sliding blocks to move the latter away from each other on the suction stroke of said piston and effect a positive closing of the said valves.

55 2. In an apparatus of the character described, in combination, a pump cylinder provided at one end with valve chambers, fluid inlet and outlet valves located in said chambers, devices movable in said valve chambers and coöperating with said valves to close the same, a piston in said cylinder, a cone attached to said piston to move therewith and coöperating with said devices to effect a closing of said valves when the 60 said piston is moved on one stroke and to

permit said valves to be opened when the piston is moved on its stroke in an opposite direction.

3. In an apparatus of the character described, in combination, a pump cylinder 70 provided at one end with a fluid inlet and with a fluid outlet, valves controlling said fluid inlet and outlet, a piston in said pump cylinder, and means attached to said piston and coöperating with said fluid outlet valve 75 to close the latter on the suction stroke of said piston.

4. In an apparatus of the character described, in combination, a pump cylinder provided at one end with a fluid inlet and 80 with a fluid outlet, valves to control said fluid inlet and outlet, a piston in said cylinder, a spring to move said piston on its suction stroke, and means movable within said cylinder with said piston to positively close 85 one of said valves on the suction stroke of said piston.

5. In an apparatus of the character described, in combination, a pump cylinder provided with a fluid inlet and with a fluid 90 outlet, a piston in said cylinder, a valve for controlling said fluid outlet automatically opened on the discharge stroke of said piston, and means attached to said piston within the cylinder for positively closing 95 said outlet valve on the suction stroke of said piston.

6. In an apparatus of the character described, in combination, a cylinder, a valve chamber communicating therewith, a valve 100 in said chamber controlling the passage of fluid from said cylinder, a device movable in said valve chamber and coöperating with said valve to move the same, a piston in said cylinder having its piston rod extended into 105 said valve chamber, and means movable with said piston rod and coöperating with said device for effecting a closing of said valve when the piston is moved in one direction.

7. In an apparatus of the character described, in combination, a cylinder, a valve chamber communicating therewith, a valve in said chamber, a piston in said cylinder, having its piston rod extended into said valve 115 chamber, a device coöperating with said valve and movable laterally with relation to said piston, means movable with the piston rod and coöperating with said device for positively closing said valve and maintaining it closed until the piston is moved.

8. In an apparatus of the character described, in combination, a cylinder, a valve chamber communicating therewith, a valve in said chamber, a piston in said cylinder, a device coöperating with said valve and movable laterally with relation to said piston, and means movable with the piston and coöperating with said device for positively closing said valve and for maintaining it 125 130

closed by movement of the piston in one direction and to permit said valve to be opened by movement of the piston in the opposite direction.

- 5 9. In an apparatus of the character described, in combination, a cylinder provided at one end with a fluid inlet and a fluid outlet, valves controlling said inlet and outlet, a piston in said cylinder, a device coöperating 10 with one of said valves and movable laterally with relation to said piston, and means movable with the piston and coöperating with said device for positively closing one of said valves and for maintaining it 15 closed.
10. In an apparatus of the character described, in combination, a cylinder provided at one end with a fluid inlet and a fluid outlet, valves controlling said inlet and outlet, 20 a piston in said cylinder, devices coöperating with said valves and movable laterally with relation to said piston, and means movable with the piston and coöperating

with said devices for positively closing both of said valves and for maintaining them 25 closed.

11. In an apparatus of the character described, in combination, a cylinder provided with a fluid outlet, a piston in said cylinder, and means operatively connected 30 with said piston to be positively moved thereby for cutting off communication between said cylinder and its outlet on the suction stroke of said piston.

12. In an apparatus of the character described, in combination, a cylinder provided with a fluid outlet, a piston in said cylinder, a valve coöperating with said fluid outlet and means operatively connected with 35 said piston within said cylinder to be positively moved by said piston to close said outlet on the suction stroke of said piston.

In testimony whereof, I have signed my name to this specification.

FREDERICK O. KILGORE.
